UNITED STATES PATENT OFFICE.

CHARLES A. LINDSTRÖM, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

TANK-VALVE AND DISCHARGE-PIPE.

1,335,445.

Specification of Letters Patent. Patented Mar. 30, 1920.

Application filed August 23, 1916. Serial No. 116,469.

To all whom it may concern:

Be it known that I, CHARLES A. LINDSTRÖM, a citizen of the United States, residing at No. 138 Stratford avenue, E. E. Pittsburgh, in the county of Allegheny and State of Pennsylvania, have invented certain new and useful Improvements in Tank-Valves and Discharge-Pipes, of which the following is a specification.

10 This invention relates to improvements in devices used in railroad tank cars to enable the contents of the tank to be discharged through a discharge opening in the bottom of the tank.
15 Such devices have hitherto consisted of a lift valve or turning plug having their seats made integral with the discharge pipe, or connected directly thereto by screw threads or other means, a screw cap being 20 located at the lower end of the discharge pipe by which means any leakage through the valve will be retained in the discharge pipe, which extends below the tank and in many instances below the car sills, to permit 25 the application and removal of the screw cap or to attach a hose to draw off the contents. In the event of an accident to the tank car, such as derailment of the car, or the shifting of the tank on the underframe 30 or other causes, the discharge pipe, which, as stated before, projects below the bottom of the tank, is liable to become damaged or broken, in fact these pipes are frequently broken, and breakages cause the valves to unseat with a consequent leakage and loss of 35 contents of the tank, and should the tank contain lading of an inflammable nature, there is an additional risk of damage and loss by fire.

40 An object of this invention is to make an arrangement of tank valve, valve seat and discharge pipe which will avoid the disadvantages above referred to and still be simple and inexpensive.

45 A further object of this invention is to construct and apply the discharge pipe to the tank in such a manner that in the event of the discharge pipe being accidentally bent or broken, the valve and seat, and their 50 positions relative to each other, will not be

disturbed, with the result that the contents of the tank will not be permitted to escape from the tank as the result of such accident.

Another object of the invention is to provide a discharge pipe and screw cap entirely 55 separate and independent from the valve and valve seat, but so arranged that there is no difference in the operation from devices in which the parts are integral.

Another object of the invention is to provide an arrangement of the discharge pipe, 60 valve seat and valve in which, when the discharge pipe gets broken, leakages through the valve can be collected by putting a cap or plug at the lower end of the valve seat, 65 or a hose may be attached to the lower end of the valve seat to draw off the contents of the tank and thus make the tank serviceable until a new discharge pipe can be provided, all of which greatly add to the safety of 70 transportation and to facilities for discharge of lading.

In the accompanying drawings, in which like reference characters refer to like parts, Figure 1 is a plan view of a portion of the 75 interior of a tank provided with the valve, valve seat and discharge pipe of this invention; Fig. 2 is a vertical section taken on the longitudinal center line of the tank, showing the valve, valve seat and discharge pipe, 80 Fig. 3 is a cross section of a portion of the tank taken through the valve, valve seat and discharge pipe, and Fig. 4 is a vertical section taken on the longitudinal center line of the tank, showing the application of this 85 invention to a different type of valve and valve seat.

Referring now in detail to the drawings, 1 indicates portion of the plate forming the shell of the tank, which may be of cylindrical or any preferred shape and carried on the usual underframe and wheeled trucks. 90 2 indicates an opening in the plate 1, and 3 a circular valve seat member having a portion 4 for the valve 5 to seat upon and form a seal to prevent the escape of the contents of the tank. 6 indicates a downwardly extending extension of the valve seat member 3, adapted to engage with guide members 7 formed on the downwardly extending 95 100

portion 8 of the valve member 5. The valve seat member is provided with flange portions 9 adapted to contact with and be secured to the plate 1, by rivets or other suitable means. 10 indicates the valve operating stem which may be connected to the valve 5 in any preferred manner, said stem extending upwardly through the interior of the tank and equipped with suitable operating means. 11 indicates the discharge pipe which is shown as having a tapering portion 12, provided with a flange 13, by which it is secured to the tank plate 1 by any suitable means. At its lower end it is provided 15 with a portion 14 having a screw thread 15 formed therein by means of which the screw cap 16 is secured to the end of the discharge pipe.

The downwardly extending portion 6 of 20 the valve seat member 3 is preferably provided with a suitable screw thread 17 with which the cap member 16 is adapted to engage, so that in the event of the discharge pipe 11 being broken, the cap member 16 25 can be applied and form a tight seal to prevent loss of any lading which may leak past the valve and seat.

Further in the event of breakage of the discharge pipe, a hose coupling may be attached to the screw threaded portion 17 of 30 the valve seat member 3, thus enabling the contents of the tank to be drawn off, and the tank to be made serviceable until a new discharge pipe can be applied.

Fig. 4 shows in section the application of 35 this invention to another type of valve and valve seat, the valve being provided with an upwardly extending guide portion 18 adapted to be guided in an upwardly extending cage-like portion 19 of the valve seat. This valve seat also is provided with a cap member 20, and spring 21, which are intended to assist in retaining the valve on its seat. The lower portion of the valve seat 40 member is furnished with a screw threaded end and cap, as described in connection with the construction shown in Figs. 2 and 3.

It will be readily observed that in the 50 construction just described there is no direct connection whatever between any portion of the discharge pipe and the valve seat, and that in the event of the discharge pipe being broken, such breakage will not be likely to affect the valve and seat.

I do not limit the invention, however, to 55 the use of the two types of valves and valve seats shown in the drawings as it is plain that any other types may be used without departing from my invention.

What I claim is:

1. The combination with a tank of a discharge opening in the bottom of said tank, a valve seat member and valve for closing 125 said opening, said valve seat member being

secured to the outside of said tank, and a discharge pipe, separate from and independent of said valve seat member, secured to said tank independently of and inclosing said valve seat member, said valve seat member extending into said discharge pipe. 65

2. The combination with a tank, of a discharge opening in the bottom of said tank, a valve seat member and valve for closing said opening, and a discharge pipe, separate from and independent of said valve seat member, secured to the outside of said tank independently of and inclosing said valve seat member, said valve seat member extending into said discharge pipe. 70

3. The combination with a tank of a discharge opening in the bottom of said tank, a valve seat member and valve for closing said opening, said valve seat being secured to the outside of said tank, and a discharge pipe, separate from and independent of said valve seat member, secured to the outside of said tank independently of and inclosing said valve seat member, said valve seat member extending into said discharge pipe. 80

4. The combination with a tank of a discharge opening in the bottom of said tank, a valve seat member and valve for closing said opening, said valve seat being secured to the outside of said tank, and a discharge pipe, separate from and independent of said valve seat member, secured to the outside of said tank independently of and surrounding said valve seat member, said valve seat member extending into said discharge pipe. 90

5. The combination with a tank of a discharge opening in the bottom of said tank, a valve seat member and valve for closing said opening, and a discharge pipe, separate from and independent of said valve seat member, secured to the outside of said tank independently of and surrounding said valve seat member, said valve seat member extending into said discharge pipe. 100

6. The combination with a tank of a discharge opening in the bottom of said tank, a valve seat member and valve for closing said opening, a cap for closing said valve seat member, and a discharge pipe secured to said tank independently of and inclosing said valve seat member. 105

7. The combination with a tank of a discharge opening in the bottom of said tank, a discharge pipe secured to said tank, a valve seat member and valve adapted to close said opening, and a cap adapted to close said valve seat member, said valve seat member being inclosed by and independent of said discharge pipe. 115

8. The combination with a tank of a discharge opening in the bottom of said tank, a valve seat member and valve adapted to close said opening, a cap adapted to close said valve seat member, and a discharge pipe 125

secured to said tank independently of and surrounding said valve seat member.

9. The combination with a tank of a discharge opening in the bottom of said tank, 5 a valve seat member and valve for closing said opening, a discharge pipe secured to said tank independently of and surrounding said valve seat member, and a cap member

adapted to be secured to either said valve seat member or said discharge pipe.

In testimony whereof I affix my signature in the presence of two witnesses.

CHARLES A. LINDSTRÖM.
